UNITED STATES PATENT OFFICE.

FRANKLIN M. RAYMOND, OF SAUGATUCK, CONNECTICUT.

CAB CONTROL SYSTEM.

1,168,908.

Specification of Letters Patent. Patented Jan. 18, 1916.

Application filed April 23, 1913. Serial No. 762,979.

To all whom it may concern:

Be it known that I, FRANKLIN M. RAYMOND, a citizen of the United States, residing at Saugatuck, in the county of Fairfield 5 and State of Connecticut, have invented certain new and useful Improvements in Cab Control Systems, of which the following is a full, clear, and exact description.

This invention relates to improvements in 10 cab-control systems for steam and electric railways.

One of the objects of my invention is to provide a cab-signaling means which will continuously indicate in the cab the position 15 of the roadside signals.

Another object of my invention is to provide an automatic train-stop mechanism which will be put into operation upon a disregard of the danger signal by the operator, 20 but not until the train has proceeded a predetermined distance into the block.

Another object of my invention is to provide an improved form of train-stop device in which the power may be cut off and 25 the brakes and sand applied at predetermined time intervals.

A further object of my invention is to utilize the air pressure from the train-pipe to operate the respective valves of the power, 30 brake and sand devices.

With these and other objects in view my invention consists in the improved construction and combinations which will be hereinafter set out in the specification and claims 35 appended hereto.

In the drawings, Figure 1 is a perspective diagram of my entire system; Fig. 2 is a diagram of the circuits and the train control mechanism; Fig. 3 is an elevation of 40 the relay; Fig. 4 is a sectional plan view taken on the line 4-4 of Fig. 3; and Fig. 5 is a detail of the lock for the armature.

Referring first to Fig. 1, a plurality of 45 roadside signals 1 are located along the trackway at any desired space intervals or, if desired, may be placed at the turn-outs. The semaphores 2 of these signals are controlled by means of track circuits in any well known manner, or may be positively 50 operated from a tower. Connected to the arm of the signals 2 is a conductor 4 which is in circuit with a battery 3, the other side of which is grounded. The arm of the semaphore is adapted to contact with stationary 55 contact 5 in its danger-indicating position, which contact leads by means of conductor 6

to a short length section 7 which is supported above the track by poles and guy-wires. This short length wire 7 is positioned over one side of the trackway instead of directly over the middle part of the trackway, so that it will not interfere with the usual trolley wire if the system is used in connection with electric railways. Connected to the short length section 7 by means of a conductor 8 is a second section 9 which is similar to section 7 and is supported in the same manner. The section 9 is spaced from section 7 a sufficient distance so that if the operator sees a danger signal and passes the same, he will have time to stop the train before reaching the section 9. Supported adjacent and parallel to the short length section 7 is a third section 11 connected to the wire 10 which terminates in a contact 10' adapted to contact with the arm of the semaphore 2 when the same is in its safety-indicating position. Contactors 12 and 13, adapted to contact with sections 7 and 11, respectively, are carried by a cab and are connected through a relay (not shown), to the lights 14 and 15, respectively, which are adapted to indicate in the cab the danger and clear positions of the roadside signals in a manner which will hereinafter be described.

The relay to which contactors 12 and 13 are connected, is shown in detail in Figs. 3, 4 and 5, wherein electromagnets 16 and 17, each comprising two coils, are supported on a frame 18 by means of the upright supports 19 and 20, respectively, which are secured to the lower ends of the cores of the electromagnets. These cores are preferably rectangular in form, each coil of the electromagnets 16 and 17 having a separate core through which the magnetic circuits are completed by the armatures 21 and 22, respectively, which are pivoted to the upright supports 19 and 20. Fastened beneath each of these armatures is a strip or block of insulation 23 and 24, each of which carry two spring-contacts 25, 26, and 27, 28, respectively. The contact 26 is adapted to rest on contact 29 and contact 27 on contact 30, when the respective armatures are in their lower or unattracted position. Contacts 25 and 28 are adapted to contact with the lower ends of substantially U-shaped contacts 31 and 32 when the armatures are in their upper or attracted position. The contacts 29, 30, 31 and 32 are mounted on

a bar made of insulating material which extends parallel to the armatures of the electromagnets 16 and 17, but below the same, and is supported by two vertically depending supports 33, 34, carried by the cross-pieces 33' and 34'. These supports are threaded (not shown) and the bar is held between two nuts carried by each of the supports so that the bar may be readily adjusted to properly contact with the spring contacts carried by the armatures 21, 22. The upper ends of the cores of the electromagnets are joined together by plates 35 and 36, respectively. These plates are made of brass or some other non-magnetic substance and are securely fastened to the yokes. Depending from the under side of the plates are the locking magnets 37, 38, which are suspended from the plates by passing the ends of the cores through poles in the plates and securing the same in place. Each of the armatures 37' and 38' for these locking coils is pivoted at its inner end to a support of brass or the like fastened to the rectangular cores of one of the pairs of the electromagnets 16 and 17, the upper portion of said support being bifurcated in which the end of the armature is pivoted. Depending from the inner ends of armatures 37' and 38' are substantially hooked-shaped portions 39 and 40, which, when the armatures of the locking coils are energized, are adapted to catch beneath the inner ends of the armatures 21 and 22, respectively, and retain the same in their upper or attracted position, as is clearly shown in Fig. 5. The armatures for the locking coils are provided with adjustable back-stops in order to regulate the lower position of the armatures. Positioned adjacent to locking coil 37 is a second coil 41 which is fastened to a portion of the support 19 bent at right angles to the main portion and which is designated 42 on the drawing. The coil 41 is provided with an armature 42' pivoted at its outer end to a support 43 depending from the plate 35, and carries at its inner end an arm 44. Extending laterally from the armature 21 is a lug 48 having a slot therein through which a rod 46 passes. This rod is supported on the lug by means of a spring 47, one end of which is fastened to the rod and the other end of which rests directly upon the face of the lug. The upper end of the rod 46 passes through an opening in the plate 35 in which the rod is keyed to prevent it from rotating. The rod 46 carries a cone-shaped projection 45 upon the flat surface of which the arm 44 carried by the armature 42' is adapted to rest and to hold the rod against upward vertical movement if the coil 41 is energized. Attached to the upper end of the rod is a contact-disk 47' made of conducting material and insulated from the remaining portion of the rod. This contact 47' is adapted

to bridge contacts 48 and 49 carried by the under side of the plate 35 but insulated therefrom, when the rod 46 is in its upper position, closing the circuit to the train controlling means, the specific circuit arrangement of which will be hereinafter described in detail in the operation of the system. 70

Referring to Fig. 2 of the drawing, the train controlling means is shown which is adapted to control the power supply and the application of the brakes and sand in the order named. Reference character 50 designates the train-pipe which extends throughout the train and which is connected to cylinders 51, 52 and 53, respectively, 80 through electromagnetically operated valves 54, 55, and 56. These valves are similar in construction and consist of the usual type of needle-valve, which are automatically operated by the electromagnets 54', 55', and 56', so that the valves will be opened and the air admitted to the cylinders when the magnets are energized. The cylinders 51, 52 and 53 are furnished with pistons which are normally positioned at one end of their stroke by compression-springs, and are connected by connecting rods to the movable portions 58', 59' and 60' of the valve 58, 59 and 60 which are respectively located in a pipe for supplying sand to the tracks, the 90 brake-line and the steam supply. When the valves 54, 55 and 56 are opened, the fluid medium will be admitted to the cylinders and the pistons will be forced to the other end of the cylinders against the force of the compression-springs. The movement of the pistons and their connecting-rods will open the valves 58 and 59 which control the sand and brakes, and close the valves 60, which will cut off the power supply. Electromagnets 54' to 56', inclusive, are controlled by circuits hereinafter described in detail, 100 which are connected to the brushes 61, 62 and 63, respectively, mounted in brush-holders and spring-pressed into contact with the peripheral surface of the quadrant 64 provided with insulated segments 65, 66 and 67, upon which the brushes 61, 62, and 63 are adapted to rest in the normal position of the quadrant. The quadrant is connected so that it may be positively operated by the core of the solenoid 68. The insulated segments of the quadrant are so spaced that upon the operation of the same by the solenoid 68, brush 61 will first close its circuit and the remaining brushes 62 and 63 will close their circuits at predetermined time intervals therefrom, the circuits controlled by each of the brushes remaining closed throughout further movement of the 110 quadrant in the same direction. A dash-pot 69 of any well known construction is connected with quadrant 64 to accurately regulate the time of travel of the same. Connected to the core of the solenoid 68 is 120

115

125

130

a rod 70 provided at its outer end with a die adapted to co-act with a die-plate 71, in front of which is positioned a roll of paper 72 mounted on rollers 73 and 74. Upon the 5 operation of the train controlling means, the die will be forced against the die-plate making an impression on the paper which will record the operation of the train controlling means. The rod 70 is provided with 10 a tooth 75 which is engaged by the latch 76 connected by means of a link to the pivot-arm 77, the latch being spring-pressed into locking engagement with the tooth. After the train controlling means has been 15 operated the latch 76 will lock the rod 70 and the quadrant 64 so that the operator will have no control over the train controlling means until the latch has been lifted by the operation of the arm 77. This arm carries 20 a pawl 78 held in engagement with the teeth of a ratchet carried by a roller 74, so that when the arm 77 is operated to lift the latch 76, the roll of paper will be moved and a fresh portion of the roll positioned in 25 front of the die-plate. In this manner a record of the number of times that the train-controlling means has been operated will be secured.

The operation of the system.—Before taking up the operation of the system, it is to be noted that for the sake of clearness armatures 21 and 22 have been omitted and the contacts carried thereby have been shown as if separately mounted, also that coil 41 30 and rod 46 have been moved to the right, the armature 21 being shown in dotted lines to clearly indicate the relation of the parts.

Referring to Fig. 2, assume that the semaphore 2 is set to safety-indicating position 35 and a train is approaching thereto, the short length conductor section 11 will be energized through a circuit from the ground, battery 3, wire 4, arm 2' of the semaphore, contact 10', wire 10, to conductor section 11, 40 which, as the train passes over this portion of the trackway, will be engaged by the contactor 13 carried by the train, and the circuit will be completed through the electromagnet 17 to the ground. Armature 22 will 45 be attracted and contacts 27 and 28 carried thereby will be moved to their upper or attracted position so that the circuit will be broken between contacts 27 and 30 and closed between contacts 28 and 32. The latter contacts will close the circuit from the 50 battery 78 through wire 79, 80, green lamp 14 indicating safety-indicating position, contacts 28 and 32, 29 and 26, wire 81, locking coil 38, wire 83, back to battery 78. 55 This circuit will light the lamp 14 and energize locking coil 38. The lighting of the lamp 14 will indicate to the operator that the roadside signal which has just passed is in safety-indicating position and that the 60 track is clear. The energization of coil 38 will attract its armature so that the hooked-shaped portion 40 carried thereby will catch beneath the armature 22 and hold it in its upper or attracted position, thereby maintaining the circuit through the lamp 14 65 closed unless it is broken at the contacts 29 and 26, which are controlled by the electromagnet 16. If the train approaches a second signal, which is also at safety-indicating position, there will be no further operation 70 and the lamp 14 will remain lighted, for, even though electromagnet 17 is again energized, its armature is already in its attracted position so that the energization of the same will have no effect on the system. Assume that the train is approaching a third signal which is in danger-indicating position, in this instance, circuit will be closed 75 from the ground through battery 3, wire 4, arm 2' of the signal, contact 5, wire 6, short length section 7, wire 8 and short length section 9. As a train reaches the roadside signal which is in its danger-indicating position, the contactor 12 will engage with short length conductor section 7 and a circuit will 80 be completed through the wire 84, contact 85, coil 41, relay 86, wire 87, electromagnet 16, and thence to the ground. The completion of this circuit will therefore energize coil 41, relay 86, and electromagnet 16. The 85 energization of relay 86 will attract its armature and close the circuit to the electromagnetic bell 88, through the battery 78, wires 79, 89, coil to the electromagnet of the bell, armature of the relay 86, back to the 90 battery, by wire 90. As the relay 86 remains energized only while the contact 12 is in engagement with short length conductor section 7, this will give merely a momentary 95 audible signal to warn the operator that the 100 train passed a roadside signal set at danger against him. The energization of electromagnet 16 will attract armature 21, which carries the spring contacts 25 and 26, which will close circuit through contacts 25 and 31 105 and open contacts 26 and 29. Contacts 26 and 29, as already pointed out, are in circuit with the green light 14, so that upon the opening of circuit at this point the green 110 light will be extinguished. Closing of the contacts 25 and 31 will close the circuit from the battery 78 through wires 79, 80, lamp 15, contacts 25 and 31, 30 and 27, wire 91, to locking coil 37, wire 83, back to the battery. The circuit will be closed through the danger lamp 15 which will give a visual signal 115 in the cab to warn the operator that he has passed a roadside signal which is set against him. The energization of locking coil 37 will attract its armature and lock the armature 21 in its upper or attracted position and the circuits controlled by the spring contacts 25 and 26 will remain closed. After 120 the train has passed a short length section 7, the armature 21 is held in its attracted position 125 130

tion and the bridging contacts 47' carried by the rod 46 will now close the circuit through contacts 48 and 49. Circuit was not closed at this point upon the train passing the short length conductor section 7 due to the fact that the coil 41 was energized, which would attract its armature 42 and the arm 44 carried thereby, so that this arm would engage with projection 45 and would 10 positively prevent the vertical rod 46 from moving with the armature 21 upon the energization of electromagnet 16. As the energization of the coil 41 depends upon the circuit being closed through contactor 12 and 15 short length section 7, as soon as a train has passed over this point the coil 41 will become deenergized and the compression-spring carried by rod 46 will force the contact 47' into bridging relation with contacts 20 48 and 49. If the operator does not immediately slow down the train, the contactors 12 will engage with short length conductor section 9 which will complete a circuit through the same contactor 12, wire 84, contacts 48, 47' and 49, wire 92, emergency switch 93, wire 94, through the solenoid 68, to the ground. This circuit will control the 25 operation of the quadrant 64 and circuits will be closed successively from the ground, through battery 78 and wires 89, 95, solenoid 56', wire 96, brush 61, quadrant 64, to the ground; through wires 89, 95, solenoid 55', brush 62, to the ground; and through 30 wires 89, 95, solenoid 54', brush 63, to the ground, which circuits will successively operate the valves 56, 55, and 54, respectively. The opening of the valve 56 will admit air 35 to the cylinder 53, which will close the valve 60 positioned in the pipe controlling the supply of steam to the locomotive and will thereby cut off the power. The opening of 40 the valves 54 and 55, will, in a like manner, open the valves 58 and 59, which will control the operation of the brakes and sand. The 45 dash-pot 69 controls the movement of the quadrant 64, but it is to be noted that the movement of this quadrant must take place while the contactor 12 is in engagement with the short length conductor section 9, or, 50 in other words, while the solenoid 68 remains energized.

The operation of the recording mechanism is apparent from the description thereof, and upon each operation of the train-controlling mechanism, an accurate record will be maintained. This recording mechanism may be so incased that the operator will have no access thereto, in order to prevent tampering therewith. The emergency switch 93, above referred to, is placed in the system, so that under certain conditions it may be desirable to cut out the operation of the train-controlling means entirely, as, for example, in a case of a wreck, where it is

desired to pass over a system in which the signals are set at danger.

While the system which has been described is specifically shown as an overhead construction, it is to be understood that the same is equally applicable to a system in which the short length conductor sections 7, 9 and 11, are placed along the trackway, and in the claims, the term "ramp" as used, is deemed broad enough to cover either of such constructions.

Furthermore, the system may be applied to electric railways, in which case a switch for cutting off the electric power would be substituted for the valve controlling the supply of steam.

Having described my invention, I claim:

1. In combination, electrically controlled "clear" and "danger" signals carried by a car, separate circuits for said signals, separate relays for closing each circuit, each of said circuits having contacts therein controlled by the armature of the relay for the other circuit and arranged to be opened when said armature is attracted to close its corresponding signal circuit, ramps along the trackway, one for each of said signals, means for energizing said ramps, and means for energizing each of said relays upon the passage of a car over a corresponding ramp when said ramp is in energized condition.

2. In combination, electrically controlled "clear" and "danger" signals carried by a car, separate circuits for said signals, separate relays for closing each circuit, each of said circuits having contacts therein controlled by the armature of the relay for the other circuit and arranged to be opened when said armature is attracted to close its corresponding signal circuit, ramps along the trackway, one for each of said signals, means for energizing said ramps, means for energizing each of said relays upon the passage of a car over a corresponding ramp when said ramp is in energized condition, and means for locking the armature of each of said relays in closed position until the circuit to the corresponding signal has been opened.

3. In combination, electrically controlled "clear" and "danger" signals carried by a car, separate circuits for said signals, separate relays for closing each circuit, each of said circuits having contacts therein controlled by the armature of the relay for the other circuit and arranged to be opened when said armature is attracted to close its corresponding signal circuit, ramps along the trackway, one for each of said signals, means for energizing said ramps, means for energizing each of said relays upon the passage of a car over a corresponding ramp when said ramp is in energized condition, and means for locking the armature of each

- of said relays in closed position until the circuit to the corresponding signal has been opened, said means comprising an electro-responsive device directly connected to the signal circuit.
4. In combination, train controlling means carried by the car, electrically-controlled operating means therefor, two energized ramps spaced along the trackway, means controlled by the passage of the car over the first of said ramps to initially control the operation of said operating means, and by the passage of the train over the second of said ramps to complete the operation of the same and means for preventing said operating means from actuating said train controlling means while the car is passing over the first of said ramps.
5. In combination, train controlling means carried by a car, electrically controlled operating means therefor, two devices spaced along the trackway, means controlled by the passage of the car over the first of said devices to initially control the operation of said operating means and by the passage of said car over the second of said devices to complete the operation of the same, and means for positively preventing said operating means from actuating said train controlling means while the car is passing over the first of said devices.
6. In combination, "clear" and "danger" signals carried by the car, circuits for each of said signals, electro-magnetic means, one for each circuit, devices along the trackway for momentarily energizing each of said electromagnetic means to close its respective circuit and to open the other circuit, and means associated with each of said electromagnetic means for maintaining each circuit when closed in closed position.
7. In combination, a train controlling means carried by a car, electrically controlled operating means therefor, means including the circuit on the car and spaced ramps along the trackway co-operating therewith to actuate said operating means, said circuit being normally opened at a point other than the one at which it is closed by co-acting with said ramps, and means on the car co-acting with the first of said ramps for closing said circuit at said last named point only after the car has passed out of contacting relation with the first of said ramps along the trackway.
8. In combination, train controlling means, electrical means for operating the same including a normally open cab circuit carried by the car, two ramps spaced along the trackway adapted to be energized under determined traffic conditions, a relay on the cab, connections whereby said relay is momentarily energized when the cab passes over the first of said ramps, if said ramp is in energized condition, means for locking the armature of said relay in its attracted position, means controlled by the armature in its attracted position for closing the cab circuit, means for preventing the action of said last named means, while said connections are energized by the first of said ramps, said closed cab circuit being energized, when the cab passes over the second of said ramps, if the ramp is in energized condition whereby the said train controlling means is operated.
9. In combination, a plurality of roadside signals each having at least two indicating positions, ramps along the trackway one for each of the indicating positions of each roadside signal, means for energizing each ramp controlled by the corresponding signal when in a corresponding indicating position, electric signals carried by the car, one for each indication of a roadside signal, separate circuits on the car for each signal, means including separate electro-responsive devices carried by the car for closing the circuit to one of said signals and opening the circuit to the other of said signals as the car passes over an energized ramp, and means for maintaining said last named circuit closed until the electro-responsive device for the other signal is energized from a corresponding ramp along the trackway.
10. In combination, a plurality of signals along the trackway each having two different indicating positions, ramps, one for each position of each signal, means for energizing said ramps controlled by its corresponding signal when in corresponding indicating position, electric signaling means carried by the car, one for each indicating position of the roadside signals, signal circuits for each of said means, electro-responsive means controlled by each of said ramps when energized for closing the circuit to one and opening the circuit to the other of said signaling means when the car passes over said ramps, and separate locking means controlled by each of said signal circuits acting upon said electro-responsive devices for maintaining it in position to maintain the corresponding signal circuit closed until said signal circuit is opened by the energization of the other of said electro-responsive devices by a passage of the car over a corresponding ramp when energized.
- In witness whereof, I subscribe my signature, in the presence of two witnesses.
